UNITED STATES PATENT OFFICE.

PAUL EBERWEIN, OF JACKSON, MICHIGAN.

DUST-COLLECTOR.

SPECIFICATION forming part of Letters Patent No. 633,954, dated September 26, 1899.

Application filed July 13, 1899. Serial No. 723,647. (No model.)

To all whom it may concern:

Be it known that I, PAUL EBERWEIN, a citizen of the United States, residing at Jackson, in the county of Jackson and State of Michigan, have invented new and useful Improvements in Dust-Collectors, of which the following is a specification.

This invention relates to that class of dust-collectors which comprise upright filtering-chambers which are open at the top and bottom, an upper chamber into which the dust-laden air is blown and from which it passes into the filtering-chambers, and a lower chamber which receives the separated dust from the filtering-chambers and from which the dust is discharged, while the purified air escapes through the cloths of the filtering-chambers into the surrounding atmosphere.

My invention has for its objects to construct the dust-collector in such manner that a large area of efficient filtering-surface is secured in a comparatively small space, that any of the filtering-chambers can be readily removed when necessary for cleaning or repairing, and that access can be readily had to both sides of each filtering-cloth, that the dust-collector is simple in construction and capable of being produced at comparatively small cost, and that a thorough and automatic cleaning of the filtering-cloths is effected.

In the accompanying drawings, consisting of four sheets, Figure 1 is a longitudinal section of a dust-collector provided with my improvements. Fig. 2 is a vertical cross-section of the same in line 2 2, Fig. 1. Fig. 3 is a perspective view showing one of the filtering-chambers and a portion of the lower dust-chamber. Fig. 4 is a longitudinal vertical section showing the inner filtering-chambers of each group, with the cut-off slides in their central position. Fig. 5 is a fragmentary horizontal longitudinal section of the dust-collector in line 5 5, Fig. 1, showing one group of filtering-chambers and one of the chambers of the other group. Fig. 6 is a fragmentary horizontal section through the upper dust-chamber in line 6 6, Fig. 1, showing a portion of the upper cut-off slide. Fig. 7 is a horizontal section, on an enlarged scale, of the transverse springs of one of the filtering-chambers. Fig. 8 is a horizontal section, on an enlarged scale, through the side portion

of one of the filtering-chambers. Fig. 9 is an enlarged vertical section of one of the cross-bars of the lower slide and a portion of the top of the lower dust-chamber. Fig. 10 is a vertical section showing a modified construction of the machine.

Like letters of reference refer to like parts in the several figures.

A A' represent the two groups of upright filtering-chambers; B, the upper dust-chamber, into which the dust-laden air is delivered by a blast-spout b; C, the lower dust-chamber, which receives the separated dust from the filtering-chambers, and D the posts or uprights, which connect the upper and lower chambers at the corners thereof.

The upper and lower dust-chambers extend from end to end of the machine, and the filtering-chambers, which are flat and rectangular in form, are arranged transversely in an upright position between the bottom d of the upper dust-chamber and the top e of the lower dust-chamber. The filtering-chambers are open at their upper and lower ends, and the bottom d of the upper dust-chamber and the top e of the lower dust-chamber are provided, respectively, with transverse slots d' d' e' e', so arranged that the filtering-chambers communicate with these slots when in place.

The filtering-chambers are arranged in two groups, each extending from one end of the machine to near the middle thereof, and each composed of a suitable number of chambers. Each filtering-chamber is constructed as follows:

F represents light rectangular wooden frames composed of uprights or stiles f and top and bottom cross-pieces f'.

f' represents the filter-cloths, which are arranged on the inner or opposing faces of each pair of frames F and secured to the frames by tacks or in any other suitable manner.

Two of these frames F are secured to opposite sides of interposed upright side pieces g by bolts g', Figs. 3 and 8. The outer portion of each side piece g is preferably somewhat wider than its inner portion, which latter is arranged between the frames and the side pieces and closes these joints. The side pieces g close the spaces between the stiles f of the two cloth-frames F, but leave the spaces between the two opposing cross-pieces f' un-

obstructed, except at the sides, thus leaving each chamber open at the top and bottom. The slots d^1 d^2 e^1 e^2 in the upper and lower dust-chambers are of the proper size to register with these openings of the filtering-chambers.

Each cross-piece f' of the filtering-chamber is constructed with a rabbet or offset h , which overlaps a rail or cleat h' , arranged transversely between every two of the slots in the bottom of the upper dust-chamber and the top of the lower dust-chamber. The two rabbeted cross-pieces f' of the top or bottom of the same dust-collecting chamber fit between two adjoining rails or cleats h' , which latter form transverse guideways, into which the chambers are slid for placing them in the proper position between the upper and lower dust-chambers. Each rabbeted cross-piece f' laps over half the width of the rail, so that each rail receives the cross-pieces of two adjacent filtering-chambers.

Each of the frames F is provided at its middle with a transverse wooden spring I, which is secured with its ends to the stiles f of the frame and extends across the open space of the frame. The inner face of the spring is straight and flush with the inner faces of the stiles, so that the filter-cloth lies snugly against the same and may be fastened thereto, if desired. The outer side or back of the spring is considerably thicker at the middle than elsewhere, as shown at i, and of such size that the back of the spring of one filtering-chamber bears against the back of the adjacent spring of the adjoining chamber.

k represents space-blocks, which extend in each filtering-chamber from the spring of one cloth-frame F to that of the opposing cloth-frame, thus establishing a rigid connection from one frame to the other. Two of these blocks are preferably employed side by side in each chamber near the middle thereof and secured by screws or otherwise to one of the springs; but one centrally-arranged block may be employed, although that construction is less effective. These blocks are preferably constructed with inclined upper sides to shed the dust which falls on them.

k' represents an upright wooden strip which is arranged midway between the stiles f of each cloth-frame F to support the cloth when the frame is so wide that a central support is desirable.

k^2 represents longitudinal strips, which are secured along the front and rear sides of the bottom and top d e , respectively, of the upper and lower dust-chambers. These strips project downwardly beyond the bottom d and upwardly beyond the top e and bear against the narrow sides or ends of the filtering-chambers, holding the latter in place. The outer overlapping portion of the stiles f of the cloth-frames F are cut away at their upper and lower ends to make room for these strips, as shown in Figs. 2 and 3. Upon removing the strips k^2 on one side of the machine any one

of the chambers can be removed by sliding it out of its ways without disturbing any other chamber. Upon closing the slots which are exposed by the removed chamber by suitable strips and bridging the open space between the springs of the chambers next adjoining the removed chamber the machine can be continued in use while the removed section is being cleaned or repaired. Upon removing the fastening-bolts which connect the cloth-frames F of the removed section these frames can be separated and access can be had to the inner side of each filter-cloth for thoroughly cleaning the same if necessary or for removing the cloth from the frame and applying a fresh cloth.

L L represent two uprights arranged between the groups A A' of filtering-chambers and secured to the upper and lower dust-chambers. Each upright forms an abutment for the springs of one group of filtering-chambers and is provided with a spiral or other suitable spring l, against which the innermost spring I of the group abuts.

M is a hammer or knocker which is arranged to strike the outermost spring I of the group A of filtering-chambers, and M' is a similar knocker which strikes the outermost spring of the group A'. The blow of each knocker, delivered against the outermost spring of the group, passes through all the springs and space-blocks of the chambers in the group and is finally yieldingly received by the spiral spring. In this manner all the cloths in the same group are jarred simultaneously and very thoroughly. The knocker M is mounted on a horizontal shaft m, which is journaled in bearings secured to the adjacent end posts D. This shaft is provided at one end with an arm m', which is actuated by a finger or projection m^2 on a sprocket-wheel N. The knocker M' is arranged at the opposite end of the machine and mounted on a shaft m^3 , which is provided with an arm m^4 . The latter is actuated by a pin or projection m^5 on a sprocket-wheel N'.

O represents the upper cut-off slide, arranged upon the bottom d of the upper dust-chamber, and P the lower cut-off slide, arranged underneath the top e of the lower dust-chamber. Each of these slides is capable of a short horizontal reciprocating movement, and consists of longitudinal side pieces, which are connected by cross bars or slats. The upper slide is provided with two series of cross-bars O' O², one series to cover and uncover the slots d^1 , through which the dust-laden air is supplied to the group A of the filtering-chambers, and the other series to cover and uncover the slots d^2 for the chambers A'. The lower slide is provided with two similar series of cross-bars p p', one for the slots e^1 , through which the dust is discharged from the chambers A, and the other for the slots e^2 , through which the dust is discharged from the chambers A'. The two series of bars are so arranged on each slide that when one series

covers the corresponding slots the other series uncovers the slots with which it cooperates, and the upper and lower slides are so arranged with reference to each other that when the upper slide covers the upper slots of a group of filtering-sections the lower slide uncovers the lower slots of the same group. In the position of the parts shown in Fig. 1 the bars O' of the upper slide uncover the slots d' , leading to the filtering-chambers A, and the dust-laden air enters the same. The bars O^2 of the upper slide cover the slots d^2 , leading to the filtering-chambers A', and exclude the dust-laden air therefrom. The knocker M' is about to strike the chambers A', from which the dust-laden air is cut off, to jar the dust from the cloths. The bars p of the lower slide cover the lower slots e' of the group A of chambers to which the dust-laden air is being supplied, thereby preventing the air from blowing into the lower dust-chamber and up into the chambers A', which are about to be jarred, and the bars p' of the lower slide uncover the lower slots e^2 , so that the dust which is jarred from the cloths of the chambers A' can drop into the lower dust-chamber. The two slides are periodically moved in opposite directions, so that the position of the slides is reversed, the upper slide cutting off the dust-laden air from the chambers A and admitting the air to the chambers A' and the lower slide opening the slots below the chambers A and closing those below the chambers A'. In passing from one position to the other the cross-bars of the slides uncover all of the slots partly and simultaneously for a short period of time when the slides are, with their edges, approximately opposite the middle of the slots, as represented in Fig. 4. In this position of the slides the dust-laden air is admitted to the chambers of both groups simultaneously, whereby the filtering capacity of all the chambers is utilized simultaneously part of the time, while at other times one of the groups is cut off to allow the same to be jarred for dislodging the dust adhering to the cloths. The upper slide O rests upon the bottom d of the upper dust-chamber, and its side pieces make, preferably, a tight joint with the bottom by a longitudinal tongue and groove O^3 and are prevented from rising by guide-strips O^4 . The lower slide P bears against the under side of the top e of the lower dust-chamber and is preferably provided with a similar tongue-and-groove joint p^2 and slides upon guide-strips p^3 . As shown in the drawings, the upper slide is reciprocated by a crank q , mounted on a shaft q' and connected with the slide by a rod q^2 . The shaft q' is provided with a sprocket-wheel Q. The lower slide is reciprocated by a crank q^3 , mounted on a shaft q^4 diametrically opposite the crank q and connected with the slide by a rod q^5 . The shaft q^4 is provided with a sprocket-wheel Q'. This crank movement causes the slides to cover the slots about one-third of the time. The cross-bars of the

upper slide have sloping upper sides to shed the dust which falls on them. The lower sides of the lower slides may be similarly shaped, as shown; but this is unimportant.

As shown in Fig. 9, the top e of the lower dust-chamber is preferably provided on both sides of each slot with a packing-strip r of cotton belting or other suitable material, arranged on edge in recesses in the top and projecting slightly to make a tight joint with the cross-bar of the slide when the bar covers the slot. The bottom of the upper dust-chamber is provided with similar packing-strips.

The lower dust-chamber is provided with an endless sweep or drag S, which consists of endless chains s , carrying cross-bars s' and running around sprocket-wheels s^2 , mounted on transverse shafts s^3 , which are provided at their outer ends with driving sprocket-wheels s^4 . This drag conveys the dust to a trough s^5 , arranged transversely at one end of this dust-chamber and containing a conveyer s^6 , by which the dust is discharged. The discharge-opening s^7 of this conveyer is trapped in any suitable way to prevent the dust from being blown out through the same when the slides uncover the upper and lower slots simultaneously. Ordinarily it is sufficient for this purpose to arrange the discharge-opening s^7 above the bottom of the trough, as shown, so that it is kept full of packed dust by the conveyer. The shaft of the latter is provided with a driving sprocket-wheel t and with a pulley T, to which power is applied. An endless chain T' travels around the sprocket-wheel t , thence around the sprocket-wheel Q' of the lower slide, thence around the sprocket-wheel N of the knocker M, thence around the sprocket-wheel Q of the upper slide, thence around the sprocket-wheel N' of the knocker M', thence around the sprocket-wheels s^4 of the drag S, and thence back to the sprocket-wheel t . Any other suitable driving mechanism may, however, be employed, if desired.

It is obvious that the machine may be modified in various respects without departing from the spirit of the invention. For instance, the lower cut-off devices may be omitted, as represented in Fig. 10, by dividing the lower dust-chamber into two separate parts C' C', each of which has a separate discharge-conveyer C² or other suitable discharge mechanism.

I claim as my invention—

1. The combination with an upper chamber which receives the dust-laden air and a lower chamber which receives the separated dust, of upright filtering-chambers arranged between said chambers and communicating therewith, and upper and lower cut-off devices, arranged to open the passages by which said filtering-chambers communicate with said upper chambers while closing the passages by which said filtering-chambers communicate with the lower chamber, and vice versa, substantially as set forth.

2. The combination with an upper chamber

- which receives the dust-laden air and a lower chamber which receives the separated dust, of upright filtering-chambers arranged between said chambers and communicating therewith, upper and lower cut-off slides which control the passages leading to and from said filtering-chambers, and means whereby said slides are reciprocated in opposite directions, substantially as set forth.
10. 3. The combination with an upper chamber which receives the dust-laden air and a lower chamber which receives the separated dust, of two groups of upright filtering-chambers arranged between said upper and lower chambers and communicating therewith, and reversible cut-off devices which direct the dust-laden air into one of said groups of filtering-chambers and exclude the dust-laden air from the other group, substantially as set forth.
15. 4. The combination with an upper chamber which receives the dust-laden air and a lower chamber which receives the separated dust, of two groups of upright filtering-chambers arranged between said upper and lower chambers and communicating therewith by upper and lower passages, and upper and lower reversible cut-off devices which simultaneously open one group and close the other group of upper passages and which simultaneously close one group and open the other group of lower passages which lead from the filtering-chambers to the lower dust-chamber, substantially as set forth.
20. 5. The combination with an upper chamber which receives the dust-laden air and a lower chamber which receives the separated dust, of two groups of upright filtering-chambers arranged between said upper and lower chambers and communicating therewith by upper and lower passages, reversible cut-off devices arranged to open one group of passages and close the other group of passages simultaneously, and means whereby said cut-off devices are slowly reversed, thereby opening both groups of passages simultaneously for a time in passing out of one position to the other, substantially as set forth.
25. 6. The combination with an upper chamber which receives the dust-laden air and a lower chamber which receives the separated dust, of two groups of upright filtering-chambers arranged between said upper and lower chambers and communicating therewith by upper and lower passages, upper and lower reversible cut-off devices arranged to open one group and close the other group of upper passages and to simultaneously close one group and open the other group of lower passages, thereby admitting the dust-laden air to one group of filtering-chambers and excluding it from the other, and means whereby said cut-off devices are slowly reversed, thereby opening all the passages simultaneously in passing from one position to the other, and admitting the dust-laden air to both groups of filtering-chambers simultaneously for a time, substantially as set forth.

7. The combination with an upper chamber which receives the dust-laden air and a lower chamber which receives the separated dust, of two groups of upright filtering-chambers arranged between said upper and lower chambers and communicating therewith by upper and lower passages, upper and lower cut-off slides arranged to open one group and close the other group of upper passages and to simultaneously close one group and open the other group of lower passages, and rotary cranks whereby said slides are reciprocated, substantially as set forth.
8. The combination with an upper chamber which receives the dust-laden air and which is provided in its bottom with a series of parallel transverse openings, and a lower chamber which receives the separated dust and which is provided in its top with corresponding openings, of vertical filtering-chambers open at their upper and lower ends and arranged between said upper and lower chambers to register with the openings therein, and upper and lower cut-off slides arranged lengthwise in said upper and lower chambers are provided with cross-bars by which said openings are alternately covered and uncovered, substantially as set forth.
9. The combination with an upper chamber which has a horizontal bottom provided with a series of parallel transverse openings, a lower chamber which has a horizontal top provided with a series of corresponding transverse openings, guide-rails secured to the under side of said bottom and the upper side of said top, between the openings of said bottom and top, and posts whereby said upper and lower chambers are united to a rigid frame, of filtering-chambers, open at their upper and lower ends to register with said openings, arranged to fit between said chambers and rabbed or offset at their upper and lower ends to overlap said guide-rails, substantially as set forth.
10. The combination with a chamber which receives the dust-laden air and which is provided with a series of parallel openings, of parallel filtering-chambers communicating with said openings and provided with external springs having enlargements by which the springs of adjoining chambers bear against each other, and a knocker by which the spring of the end filtering-chamber is struck, substantially as set forth.
11. The combination with a chamber which receives the dust-laden air and which is provided with a series of parallel openings, of parallel filtering-chambers communicating with said openings, each chamber provided on opposite sides with external springs having enlargements by which the springs of adjoining chambers bear against each other, internal stay-blocks connecting the springs of each chamber, and a knocker by which the spring of the end filtering-chamber is struck, substantially as set forth.
12. In a dust-collector, a flat rectangular

filtering-chamber open at its upper and lower ends and composed of two rectangular cloth frames, each having the filtering-cloth arranged on its inner face, interposed side 5 pieces, external springs arranged across the open space of the cloth-frames, and internal stay-blocks arranged between said springs, substantially as set forth.

13. In a dust-collector, the combination with 10 a series of parallel filtering-chambers provided with internal stay-pieces and with external springs having enlargements by which the springs of adjoining chambers bear against each other, of a knocker which strikes the 15 spring at one end of the series of filtering-chambers, and a yielding abutment which supports the spring at the opposite end of the series, substantially as set forth.

14. The combination with an upper chamber 20 which receives the dust-laden air and a

lower chamber which receives the separated dust, of two groups of upright filtering-chambers arranged between said chambers and communicating therewith, and provided with external springs which bear against each other, 25 knockers arranged to strike the springs at the outer ends of the groups of filtering-chambers, yielding abutments arranged between the groups of filtering-chambers and supporting the springs at the inner ends thereof, and reversible cut-off devices whereby the dust-laden air is directed to one group of filtering-chambers and excluded from the other, substantially as set forth.

Witness my hand this 10th day of July, 35
1899.
